CLAIM

The ornamental design for the display board for a grocery list, as shown and described.

DESCRIPTION

FIG. 1 is an exploded front elevational view of the display board for a grocery list showing my new design, with the broken line showing for illustrative purposes only and forming no part of the claimed design;

FIG. 2 is an exploded rear elevational view thereof;

FIG. 3 is an exploded left side elevational view thereof;

FIG. 4 is an exploded right side elevational view thereof;

FIG. 5 is an exploded top plan view thereof;

FIG. 6 is an exploded bottom plan view thereof; and,

FIG. 7 is a perspective view thereof.
